UNITED STATES PATENT OFFICE.

PAUL F. ZIETLOW, OF BROOKLYN, NEW YORK.

COMBINED ATOMIZER AND VAPORIZER.

1,354,641.

Specification of Letters Patent.

Patented Oct. 5, 1920.

Application filed October 30, 1919. Serial No. 334,397.

To all whom it may concern:

Be it known that I, PAUL F. ZIETLOW, a citizen of the United States, residing at Brooklyn, in the county of Kings and State 5 of New York, have invented certain new and useful Improvements in Combined Atomizers and Vaporizers, of which the following is a specification, reference being had to the accompanying drawings.

10 This invention relates to a combined atomizer and vaporizer, and an object is to provide a device of this kind which is very simple in construction, and capable of being manufactured at relatively low cost and sold 15 at a reasonable profit.

Heretofore, atomizers have been equipped with adjustable tubes, not adjustable to form a pronounced chamber beyond the atomizer nozzle whereby the atomizer may be converted 20 into a vaporizer, but movable simply to provide an adjustable plug or nozzle.

The present invention aims to provide an elongated tube so adjustable on the spray nozzle of the atomizer as to provide a very 25 pronounced elongated chamber, beyond the nozzle of the atomizer, so as to break up the liquid spray into a vapor before it leaves the outer end of the movable tube, thereby converting an atomizer into a vaporizer and 30 vice versa.

Another object of the invention is to provide a vaporizer construction which can be applied to any form of atomizer regardless 35 of the material of which the atomizer is constructed.

Another object of the invention is to provide a vaporizing tube, adjustable on the atomizing nozzle and which may be constructed of hard rubber, metal or any other 40 material, and may be made cylindrical, rectangular in cross section, or irregular in length, or any other shape, and also may be any suitable diameter as long as it is long enough to telescope over the atomizing tube 45 on the nozzle, whereby a very pronounced vaporizing chamber beyond the atomizing nozzle can be formed.

A further object of the invention is the provision of a vaporizing tube having a 50 conical nasal-engaging end, and furthermore to provide a construction of vaporizer and atomizer whereby the parts may be easily disassembled for cleaning readily.

A further object of the invention is to 55 provide a vaporizing tube which may be fastened in any suitable manner upon the

atomizing tube, in combination with means for limiting the vaporizing tube in its movement on the atomizing tube.

While the design and construction at present illustrated and set forth, is deemed preferable, it is obvious that as a result of reduction of the invention to a more practical form for commercial purposes, the invention may be susceptible to changes, and the right 60 to these changes is claimed, provided they are comprehended within the scope of what is claimed.

The invention comprises further features and combination of parts, as will be herein- 70 after set forth, shown in the drawings and claimed.

In the drawings:

Figure 1 is a view in side elevation of a combined atomizer and vaporizer con- 75 structed in accordance with the invention, and illustrating the vaporizing tube in section, and arranged in a position on the atomizing tube so that its outer nasal end is flush with the nozzle end of the atomizer. 80

Fig. 2 is a view in side elevation of a combined atomizer and vaporizer, showing the atomizing and vaporizing tubes both in section, the vaporizing tube being moved outwardly on the atomizing tube in order to 85 provide a pronounced chamber beyond the nozzle of the atomizing tube.

Referring more especially to the drawings, 1 designates a receptacle adapted to contain a suitable liquid to be atomized or 90 vaporized, and 2 denotes the body of the atomizing tube, which is threaded or otherwise secured to the receptacle. The atomizing tube has an extension 3, which extends down into the receptacle, upwardly through 95 which the medicinal fluid or liquid is forced so as to discharge in a spray form from the nozzle end of the atomizing tube. The usual pneumatic bulb 4 is attached, as indicated, to the body of the atomizing tube, 100 so as to force air, in the usual manner, into the receptacle so as to force the liquid upwardly through the extension of the atomizing tube.

The atomizing tube may be positioned 105 horizontally, though not necessarily, for it is obvious that it may be disposed in any other suitable position. The atomizing tube 5 is provided with a limiting abutment shoulder 6, near its rear portion. The end 110 of the atomizing tube 5 has a threaded extension 7, which has an additional extension

8. An atomizing nozzle 9 is threaded on the extension 7, so that the extension 8 will be in close position to the orifice 10 of the nozzle, whereby as the liquid reaches the extension 8, it will pass through the orifice in the form of a spray, which may be utilized for atomizing the nasal passages. The atomizing tube adjacent the threaded extension has an annular groove 11.
- 10 A tube 12 telescopically fits the atomizing tube until it contacts with the shoulder. The interior surface of the tube 12 has an annular shoulder 13. It will be noted that the end 14 of the nozzle of the atomizer is 15 of a diameter to fit the tube 12, whereby the tube 12 may move inwardly and outwardly. However, the end 14 of said nozzle of the atomizer tube is large enough in diameter so as to be engaged by the shoulder 13 of 20 the interior of the tube 12, thereby constituting means to limit the tube 12 in its outward movement. A nasal-engaging nozzle 15 is threaded upon the outer end of the tube 12 so as to constitute means to fit the 25 nasal passage and to direct the spray or vapor into the nasal passages.
- Heretofore atomizing tubes have been equipped with adjustable tubes, but these tubes simply constitute nasal plugs, and 30 not tubes to form vaporizing chambers. In the present case, the tube 12 (which constitutes a vaporizing tube) may be moved outwardly on the atomizing tube until the interior shoulder 13 contacts with the atomizing nozzle, thereby limiting the tube 12 in 35 its outward movement. When the tube 12 is limited in such a position, it will be noted that a pronounced, elongated, cylindrical chamber is formed beyond the nozzle of the 40 atomizing tube. In order to vaporize a medicinal liquid it is first necessary to provide a construction whereby an atomizing spray can be produced, after which it is necessary to discharge the spray into a very 45 pronounced chamber at a point beyond the nozzle from which the spray leaves, so that the liquid spray can readily break up into a vapor, which may discharge into the nasal 50 passages. Therefore, it may be seen that when the tube 12 is adjusted outwardly on the atomizing tube until it is limited by the shoulder 12, a very pronounced chamber is 55 formed beyond the nozzle of the atomizer, hence the spray when it leaves the nozzle of the atomizer will break up and provide a vapor that can readily discharge into the nasal 60 passages. When the tube 12 is adjusted outwardly on the atomizing tube, a certain amount of air is drawn through the 65 rear portion of the vaporizing tube 12 at the point where the annular groove is formed on the atomizing tube, and this air acts materially in causing a proper vaporization of the spray. When the vaporizing 70 tube is in contact with the shoulder at

the rear portion of the atomizing tube, and its outer end flush with the atomizing nozzle, simply a spray can be discharged from the nozzle.

The invention having been set forth, what I claim as new and useful is:

1. In a combined atomizing and vaporizing device, the combination with an atomizing tube having a spray nozzle, of a vaporizing tube adjustable telescopically upon the atomizing tube whereby it may be moved outwardly on the atomizing tube so as to provide a pronounced elongated chamber beyond the atomizing tube, in which the spray from the nozzle may break up in a vapor, and means at each end of the atomizing tube for limiting the vaporizing tube in its outward and inward movements on the atomizing tube.

2. In a combined atomizing and vaporizing device, the combination with an atomizing tube having a spray nozzle, of a vaporizing tube adjustable telescopically upon the atomizing tube whereby it may be moved outwardly on the atomizing tube so as to provide a pronounced elongated chamber beyond the atomizing tube, in which the spray from the nozzle may break up in a vapor, means at each end of the atomizing tube for limiting the vaporizing tube in its outward and inward movements on the atomizing tube, and means to permit an extra supply of fresh air to be drawn into the rear end of the vaporizing tube when it is in its outward adjusted position.

3. In a combined atomizing and vaporizing device, a tube relatively straight for the greater part of its length having a fixed shoulder at one end and an atomizing spray nozzle detachably fixed to the discharge end of the tube, a vaporizing tube having its inner diameter for the greater part of the length of the tube slightly greater than the diameter of the spray nozzle, whereby the vaporizing tube may telescope over the nozzle, the inner diameter of the other end of said vaporizing tube being slightly less than the diameter of the nozzle so as to telescope over the relatively straight portion of the atomizing tube and being capable of a limited movement between the spray nozzle and the fixed shoulder, whereby the vaporizing tube may be moved so that its outer end may be flush with the nozzle to provide an atomizer, or may be moved so that its outer end may position considerably beyond the nozzle, thereby providing a chamber in advance of the nozzle, and wherein the spray from the nozzle vaporizes.

4. In a combined atomizing and vaporizing device, a relatively straight atomizing tube having a fixed shoulder at one end, and a removable spray nozzle at the other end, one end of the nozzle being greater in diameter than the diameter of said tube, and

thereby causing a shoulder to be formed, a tube of a length substantially equaling the length of the first tube from the fixed shoulder to the end of the nozzle, said second tube having a portion thereof a little less than one half the length of the first tube between the fixed shoulder and the nozzle shoulder of a diameter to telescopically engage said first tube between the two shoulders to have limited movement, the second tube for more than half its length having an inner diameter greater than the nozzle so as to telescope thereover and cause to be formed a chamber beyond the discharge end of the nozzle, and in which the atomized fluid vaporizes as it is discharged.

5. A combined atomizing and vaporizing device comprising inner and outer telescopically united tubes, the inner tube having a spray or atomizing nozzle, the outer tube 20 being of a length substantially equaling the length of the inner tube and adapted to telescopically overlie the nozzle whereby when the outer end of the outer tube is moved beyond the nozzle, a chamber is caused to be 25 formed in advance thereof and in which the atomized fluid vaporizes, the inner and outer tubes having coöperative means for limiting the outer tube in its movement.

In testimony whereof I hereunto affix my 30 signature.

PAUL F. ZIETLOW.
